US00D942956S

(12) **United States Design Patent** (10) Patent No.: **US D942,956 S**
(45) Date of Patent: **** Feb. 8, 2022**

(54) **CONTROL DEVICE**

(71) Applicant: **Lutron Technology Company LLC**,
Coopersburg, PA (US)

(72) Inventors: **Brad Michael Kreschollek**, Bethlehem,
PA (US); **Noel Mayo**, Philadelphia, PA
(US); **Nayda Aponte**, Northampton, PA
(US)

(73) Assignee: **Lutron Technology Company LLC**,
Coopersburg, PA (US)

(**) Term: **15 Years**

(21) Appl. No.: **29/708,029**

(22) Filed: **Oct. 2, 2019**

(51) LOC (13) Cl. **13-03**

(52) U.S. Cl.
USPC **D13/162**

(57) **CLAIM**

The ornamental design for a control device, as shown and
described.

DESCRIPTION

FIG. 1 is a front view of a control device showing the
claimed design;

FIG. 2 is a left side view thereof;

FIG. 3 is a right side view thereof;

FIG. 4 is a top view thereof; and,

FIG. 5 is a bottom view thereof.

1 Claim, 2 Drawing Sheets
